UNITED STATES PATENT OFFICE.

WILLIAM S. SUTTON, OF ROCKFORD, ILLINOIS.

INTERNAL-COMBUSTION ENGINE.

1,103,325.

Specification of Letters Patent. Patented July 14, 1914.

Application filed January 6, 1913. Serial No. 740,571.

To all whom it may concern:

Be it known that I, WILLIAM S. SUTTON, a citizen of the United States, residing at Rockford, in the county of Winnebago and State of Illinois, have invented new and useful Improvements in Internal-Combustion Engines, of which the following is a specification.

The primary object of the present invention is to provide means for exploding the charge in an internal combustion engine, without the necessity of an electrical igniter or mechanism of a similar character, and also without the employment of a constant flame, hot tube, or the like. To this end, an auxiliary compression chamber is employed, in which an explosive mixture is admitted and compressed to a degree to cause its spontaneous ignition. This explosion is caused to take place at the proper time, and is communicated to the charge in the engine, so as to explode the latter.

While the invention may be embodied in various ways, one form of construction that is at present considered the preferable one, is illustrated in the accompanying drawings, wherein—

Figure 1 is a view partly in elevation and partly in section of an internal combustion engine equipped with the igniter. Fig. 2 is a detail section on the line A—A, of Fig. 1. Fig. 3 is a detail section of the clutch, as illustrated in Fig. 1, but on an enlarged scale. Fig. 4 is a sectional view at right angles to Fig. 1, and showing the plunger in a different position. Fig. 5 is a detail sectional view of the clutch in the position shown in Fig. 4. Fig. 6 is a view similar to Fig. 2, but illustrating the actuating means for the plunger in a different position. Fig. 7 is a detail view on an enlarged scale of the clutch, as shown in Fig. 6. Fig. 8 is a detail sectional view on the line D—D of Fig. 1. Fig. 9 is a view in elevation of the means for varying the time of the ignition. Fig. 10 is a view at right angles to Fig. 9. Fig. 11 is a detail sectional view on the line C—C of Fig. 1. Fig. 12 is a view similar to Fig. 11, but showing the parts in an altered relation. Figs. 13, 14 and 15 are detail horizontal sectional views on enlarged scales, and respectively on the lines E—E, F—F, and G—G of Fig. 3.

Similar reference numerals designate corresponding parts in all the figures of the drawings.

In the embodiment disclosed, the engine may be of any well known type, and comprises a cylinder 16 mounted on a crank case 17, and containing the usual reciprocating piston 18. The piston has a pitman connection 19 with the crank 20 of the usual engine shaft 21 journaled in the walls of the crank case. Any suitable means (not shown) may be employed for introducing charges to this engine and permitting the exhaust thereof.

The igniter in the present embodiment comprises a compression chamber, shown in the form of an open-ended tube 22, mounted on one side of the engine, and having communication with the interior of the chamber through a small port 23 that opens into a passage 24 through the cylinder wall. An explosive mixture from any suitable source is admitted into one end of this chamber, through a passageway 25 extending from a coupling 26, to which a supply pipe may be attached. This passageway 25 is controlled by an inwardly opening valve 27 carried by a valve stem 28 that projects from the head of the valve casing, and is surrounded by a suitable closing spring 29. The outer end of the valve stem 28 is suitably connected to the offset end 30 of an actuating rod 31, which rod reciprocates in suitable bearings 32 and 33 and terminates in a yoke 34 surrounding the engine shaft. This yoke has a roller 35 on its free end that is borne against by a cam 36.

Operating in the compression chamber 22 is a reciprocating plunger 37 formed by the end of a rod, the main portion 38 of which may be termed a plunger stem. This plunger stem extends through a casing 39 surrounding the compression chamber 22 and having a closed bottom 40, upon which rests a spring 41. The spring bears against a sleeve 42 secured to the rod within the casing 39, and having its upper end flanged and moving between the chamber 22 and said casing 39. This flanged end is borne against by the spring 41.

A reciprocating rod 43 extends through the top of the crank case, and is slidably mounted in a bearing 44. The upper end of this rod is hollowed out to receive the projecting end of the stem 38. The said stem is provided with an annular groove 45, and the end of the rod 43 has a pair of diametrically opposite openings 46, in which operate clutch balls 47 that are movable into and out

of the groove 45, as will be evident by a comparison of Figs. 5 and 7. A clutch-controlling collar 48 is slidably mounted on the end of the rod 43 over the said balls, and has an internal annular groove 49 that receives the same under certain conditions. This collar is normally frictionally held against movement on the rod 43, and to this end, a coiled spring 50 is preferably located in a groove 10 therein and binds against the said rod.

The rod 43 has a pivotal connection, as shown at 51 with the stem 52 of a yoke 53 surrounding an eccentric 54. By referring to Fig. 1, it will be noted that the eccentric 54 and the cam 36 are integral with a sleeve 55, which is keyed as shown at 56 to an inner sleeve 57 mounted on a countershaft 58. The countershaft has a 2:1 gear connection 59 with the engine shaft, and the inner sleeve 57 is provided with a pin 60 operating in a curved groove 61 formed in the countershaft 58. The said inner sleeve 57 is capable of longitudinal movement on the shaft, and in the sleeve 55, and it will be evident will have a slight turning movement with respect to said shaft 58. The movement of the said inner sleeve 57 can be secured by any suitable means, as for instance by a sector 62, the teeth of which mesh with annular ribs or teeth 63 formed on the projecting end of the sleeve. This sector 62 is carried by a stub shaft 64 mounted on the side of the crank case, and having a suitable operating lever 65 with a holding dog 66 that cooperates with the teeth 67 of a rack.

Briefly described, the operation of the igniter is as follows. Assuming the cycle to begin with the compression piston 37 in the position shown in Fig. 2, it will be noted that the clutch controlling collar 48 is in a position to hold the clutch balls 47 in the groove 45 of the plunger stem. As the eccentric 54 is rotated, the rod 43 will be moved downwardly, carrying the plunger with it, and correspondingly compressing the spring 41. During this movement, the cam 36 is operating to open the valve 27, and consequently an explosive charge is drawn into the compression chamber 22. As the said plunger reaches the limit of its down or withdrawal stroke, the clutch controlling collar 48 will strike the guide 44 located in its path. The rod, however, continues to move downwardly, and therefore the clutch balls 47 will be brought into register with the internal groove 49 in said collar. Immediately, said balls will be forced out into the groove, thereby releasing the plunger from the actuating rod 43, and the compressed spring 41 will react to suddenly return the plunger 37 to its first position. It is believed this will be clear by reference to Figs. 6 and 7. The relation of the parts is such that this sudden compression will be sufficient to cause a forcible and almost in-

stantaneous compression of the mixture in the compression chamber, so that it will be spontaneously ignited and the flame will shoot out through the small orifice 23 into the engine cylinder. At this time, the piston has compressed the charge therein, and consequently the main charge will be exploded to drive the engine. As the eccentric 54 continues its rotation, the rod 43 will again be elevated, and as it approaches the upper limit of its stroke, the clutch controlling collar 48 will strike the boss on the lower end of the casing 39. As a result, the balls will be carried above the internal groove 49 in said collar, and will therefore be forced inwardly into the groove 45. The actuating rod 43 thus becomes again clutched to the plunger stem, and the parts are in a position to have a repetition of the cycle of operation above described. The exhaust in the ignition chamber is secured by making the orifice 23 of a size that will permit the gases to be discharged from the compression chamber before a fresh charge is drawn into the same. In order to change the period of this compression and ignition with respect to the operation of the engine piston, it is only necessary to shift the lever 65, in which case, the cam 36 and eccentric 54 will be rotated upon the countershaft 58, and thus the ignition can be advanced or retarded as desired.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. The combination with an internal combustion engine, of an igniter therefor, comprising a compression chamber, means for admitting charges to the compression chamber, a charge-compressing device having a back and forth movement in the chamber, an actuating device for the charge compressing device slidably engaged therewith and also having a back and forth movement, the movement of each in one direction being independent of the movement of the other, and means for periodically connecting the slidably engaged portions of the charge compressing device and the actuating device to secure their simultaneous movement and disconnecting the same to permit their independent movement.

2. The combination with an internal combustion engine, of an igniter therefor, comprising a compression chamber, means for

admitting charges thereto, a reciprocatory charge-compressing device movable in the chamber, a reciprocatory actuating device therefor slidably telescoping therewith, said devices being capable of independent movement, and means mounted on the telescoping portion for periodically connecting the charge-compressing device and actuating device to effect the movement of the one from the other and disconnecting the same to permit one to operate independently of the other.

3. The combination with an internal combustion engine, of an igniter therefor, comprising a compression chamber, means for admitting charges thereto, a reciprocatory charge-compressing device movable in the chamber, a reciprocatory actuating device therefor, said devices being capable of independent movement, a clutch surrounding both members for periodically connecting and disconnecting the charge-compressing device and actuating device, and means for automatically actuating the clutch.

4. The combination with an internal combustion engine, of an igniter therefor, comprising a compression chamber, means for admitting charges thereto, and exhausting the ignited material therefrom into the engine, a plunger operating in the chamber, a reciprocatory actuating rod for the plunger slidably engaged therewith, a clutch element for connecting and disconnecting the rod and plunger, a controlling device movable with the rod and slidably longitudinally thereon for effecting the operation of the clutch element, and means in the path of the controlling device for shifting the same with respect to the rod.

5. The combination with an internal combustion engine, of an igniter therefor, comprising a compression chamber having communication with the engine, means for admitting a charge to the compression chamber, means for compressing the charge in the chamber, an actuating device for the compressing means slidably telescoping therewith and movable independently thereof, a device that detachably connects the actuating device and compressing means to effect their simultaneous movement, and means that periodically operates the connecting device to cause it to disconnect the actuating device and compressing means.

6. The combination with an internal combustion engine, of an igniter therefor, comprising a compression chamber having communication with the engine, means for admitting a charge to the compression chamber, means for compressing the charge in the chamber, an actuating device for the compressing means slidably engaged therewith and movable independently thereof, a device movably mounted on the slidably engaged portion of the actuating device and

detachably engaging the compressing means to effect their simultaneous movement, and means that periodically operates the connecting device to alternately cause it to connect and disconnect the actuating device and compressing means.

7. The combination with an internal combustion engine, of an igniter therefor, comprising a compression chamber having communication with the engine, means for admitting a charge to the compression chamber, means for compressing the charge in the chamber, an actuating device for the compressing means movable independently thereof, an eccentric member for continuously operating the actuating device, means for periodically connecting the actuating device and compressing means to move the latter by the former and disconnecting the same to permit the independent operation of the compressing means, and means for operating the compressing means when disengaged from the actuating device.

8. The combination with an internal combustion engine, of an igniter therefor, comprising a compression chamber, means for admitting charges thereto, a plunger operating in the chamber, a plunger-operating device, means continuously actuated by the engine and continuously moving the plunger-operating device, and an automatically operated clutch for periodically connecting and disconnecting said device and plunger.

9. The combination with an internal combustion engine, of an igniter therefor, comprising a compression chamber communicating with the engine, means for admitting charges thereto, a reciprocatory plunger member operating in the chamber, a reciprocatory operating member for the plunger member, means operated by the engine for continuously reciprocating the operating means, a clutch moving with one of said members, and engaging and disengaging the other member, and means located in the path of the clutch for automatically operating the same.

10. The combination with an internal combustion engine, of an igniter therefor, comprising a compression chamber having communication with the engine, means for admitting charges to the chamber, a plunger operating in the chamber and having a stem, means operated by the engine including a rod telescoping with the stem, a clutch mounted on the rod and movable into and out of coacting relation with the stem, means located in the path of movement of the clutch for actuating the same, and means for automatically moving the plunger to compress a charge to the ignition point when the stem is released from the rod.

11. The combination with an internal combustion engine, of an igniter therefor, comprising a compression chamber having

communication with the engine, a valved controlled charge inlet to the chamber, means operated by the engine for actuating the valve, a reciprocatory plunger operating in the chamber and having a valve stem, a spring for moving the plunger in one direction, a reciprocatory rod actuated by the engine and telescoping with the stem, a clutch carried by the rod and movable into 10 and out of engagement with the stem, and

devices located in the path of movement of the clutch for connecting the stem to and disconnecting it from the rod.

In testimony whereof I have hereunto set my hand in presence of two subscribing wit- 15 nesses.
